COMBINED FAUCET FIXTURE AND KITCHEN ACCESSORY POWER SOURCE UNIT

Herbert Carvel Moore, Los Angeles, Calif., assignor to Electro-Way Corporation, Los Angeles, Calif., a corporation of California

Filed Feb. 13, 1961, Ser. No. 63,914

Term of patent 14 years

(Cl. D91—3)

FIGURE 1 is a perspective view of a combined faucet fixture and kitchen accessory power source unit showing my new design, it being understood that the decorative pattern on the front panel which is only partially shown covers the entire panel disclosed;

The rear and bottom are devoid of ornamentation.

I claim:

The ornamental design for a combined faucet fixture and kitchen accessory power source unit, as shown and described.
